UNITED STATES PATENT OFFICE.

ANDREW J. MEGEE, OF PHILADELPHIA, PENNSYLVANIA, ASSIGNOR TO THE MILLER BIBLE AND PUBLISHING HOUSE, (LIMITED,) OF SAME PLACE.

ALBUM.

SPECIFICATION forming part of Letters Patent No. 281,102, dated July 10, 1883.

Application filed January 2, 1883. (No model.)

To all whom it may concern:

Be it known that I, ANDREW J. MEGEE, a citizen of the United States, and a resident of Philadelphia, Pennsylvania, have invented 5 certain Improvements in Albums, of which the following is a specification.

The object of my invention is to construct an album for holding cards so that the latter can be readily inserted or removed, and so 10 that the covers will not be distended when the album is filled with cards.

In the accompanying drawings, Figure 1 is 15 a perspective view of my improved card-album, showing the same opened; and Fig. 2 is an enlarged section of one of the leaves of the album.

A A are the covers of the album, and B the leaves, each of the latter having in the present instance a joint similar to that described in my Patent No. 256,022, dated April 4, 1882. 20 This, however, while preferred, is not essential. Each leaf consists of three parts—namely, the opposite sheets, a a', and the filling-piece b, the center of the latter being cut out, so as to leave simply a rim or margin around the leaf. In each of the sheets a a' are formed 25 incisions d, into which are inserted the corners of the cards to be retained, the arrangement of these incisions being such as may be sug-

gested by the size and desired disposal of the cards. By this means the cards are held in 30 position for convenient reference, but can at any time be readily removed, any desired change in the arrangement of the cards being thus permitted. The interposition of the filling-piece b between the sheets a a' prevents 35 the bulging of the covers of the album when the latter is filled with cards. Each of the sheets a a' may have printed upon it lines indicating the disposal of the cards to properly accord with the incisions in the sheets. 40

I claim as my invention—

1. A card-album consisting of covers A and leaves B, each of the latter comprising sheets a a', with incisions d, and a filling-piece, b, as set forth. 45

2. A leaf for card-albums, the same comprising sheets a a', with incisions d, and a filling-piece, b, as set forth.

In testimony whereof I have signed my name to this specification in the presence of 50 two subscribing witnesses.

ANDREW J. MEGEE.
